(57) **CLAIM**

The ornamental design for the helmet, as shown and described.

DESCRIPTION

FIG. 1 is an isometric view of a helmet showing our new design;

FIG. 2 is right side view thereof;

FIG. 3 is a front end view thereof;

FIG. 4 is a rear end view thereof;

FIG. 5 is a top plan view thereof;

FIG. 6 is a bottom plan view thereof;

FIG. 7 is an isometric view of a second embodiment thereof;

FIG. 8 is a top plan view of the helmet in FIG. 7;

FIG. 9 is an isometric view of a third embodiment thereof;

FIG. 10 is a right side view of the helmet in FIG. 9;

FIG. 11 is a front end view of the helmet in FIG. 9;

FIG. 12 is a rear end view of the helmet in FIG. 9;

FIG. 13 is a top plan view of the helmet in FIG. 9;

FIG. 14 is a bottom plan view of the helmet in FIG. 9;

FIG. 15 is an isometric view of a fourth embodiment thereof;

FIG. 16 is a right side view of the helmet in FIG. 15;

FIG. 17 is a front end view of the helmet in FIG. 15;

FIG. 18 is a rear end view of the helmet in FIG. 15;

FIG. 19 is a top plan view of the helmet in FIG. 15;

FIG. 20 is a bottom plan view of the helmet in FIG. 15;

FIG. 21 is an isometric view of a fifth embodiment thereof;

FIG. 22 is a right side view of the helmet in FIG. 21;

FIG. 23 is a front end view of the helmet in FIG. 21;

FIG. 24 is a rear end view of the helmet in FIG. 21;

FIG. 25 is a top plan view of the helmet in FIG. 21; and,

FIG. 26 is a bottom plan view of the helmet in FIG. 21.

The broken lines in all views are for illustrative purposes only and form no part of the claimed design.

The missing right, front and bottom views of the second embodiment of FIGS. 7 and 8 are the same as FIGS. 2, 3 and 6.

1 Claim, 13 Drawing Sheets
